UNITED STATES PATENT OFFICE

173,052

LIQUID APPLICATOR

Roland A. Cassia, White Plains, N. Y.

Application October 1, 1953, Serial No. 27,026

Term of patent 14 years

(Cl. D9—2)

To all whom it may concern:

Be it known that I, Roland A. Cassia, a citizen of the United States, residing at White Plains, New York, have invented a new, original, and ornamental Design for a Liquid Applicator, of which the following is a specification, reference being had to the accompanying drawing, forming part thereof.

In the drawings:

Fig. 1 is a perspective view of a liquid applicator, showing my new design;

Fig. 2 is a front view thereof;

Fig. 3 a rear view thereof;

Fig. 4 a top plan view thereof;

Fig. 5 a side elevational view thereof; and

Fig. 6 a bottom view.

The handle is broken away in Figs. 4 and 5 for the convenience of illustration only.

I claim:

The ornamental design for a liquid applicator, substantially as shown and described.
